UNITED STATES PATENT OFFICE.

FRANK M. EDMONDS, OF HOLYOKE, MASSACHUSETTS, ASSIGNOR TO COBURN TROLLEY TRACK MANUFACTURING COMPANY, OF WILMANSSETT, MASSACHUSETTS, A CORPORATION.

DOUBLE-DOOR-CLOSING DEVICE.

SPECIFICATION forming part of Letters Patent No. 778,959, dated January 3, 1905.

Application filed March 27, 1903. Serial No. 149,914.

To all whom it may concern:

Be it known that I, FRANK M. EDMONDS, a citizen of the United States of America, residing at Holyoke, in the county of Hampden 5 and State of Massachusetts, have invented new and useful Improvements in Double-Door-Closing Devices, of which the following is a specification.

This invention relates to automatic door-closing devices, and has special reference to a device of this character adapted to operate double doors, one of which must be closed before the other. This type of door-closing devices is usually associated with some means whereby the devices are held in restraint normally and which means may be automatically operated to effect the release of the door-closing devices. Usually there has been associated with the restraining means a strip of easily-fusible metal adapted to rupture under abnormally high temperatures to release the door-closing devices, or associated with said restraining means may be some other, as an electrically-operated device, whereby upon the opening or closing of a circuit said restraining means may be operated to release the door-closing device.

The object of this invention is to improve the construction of the door-closing devices 30 whereby the closing of the doors in succession instead of simultaneously is assured; and to that end the invention consists in the devices described in the following specification, and pointed out in the claims.

In this application releasing means, both thermally and electrically operated, are shown in association with the door-closing devices; but the invention runs particularly to the construction of the door-closing devices, and the 40 thermal or the electric devices whereby they are controlled are not considered as a part of the invention except as they may constitute an element of some claim in combination with the door-closing devices.

In the drawings forming part of this application, Figure 1 shows a portion of two open doors and the devices for closing the doors applied thereto according to this invention.

Fig. 2 is a top plan view, considerably enlarged, of the weight-restraining devices and 50 their supports. Fig. 3 is a front elevation of the same. Fig. 4 is a sectional view on line 4-4 of Fig. 3 looking to the left. Fig. 5 is a similar view on line 5-5 looking to the right, same figure. Fig. 6 is a perspective view of 55 a spiral-faced boss to be attached to one of the doors. Fig. 7 is a perspective view of one end of a sliding bolt, having a spirally-formed end similar to that on the boss shown in Fig. 6.

Referring now to the drawings, *a* and *b* indicate, respectively, two doors, *a* being the door which is to be closed first, the doors being hung in any suitable manner to swing toward and from each other. In the door-opening, preferably on one side thereof near the 65 top, the door-closing devices are located and suitable chains or other flexible connections, as *c* and *d*, are attached near the upper corners of each door by one end, their opposite ends leading through or over suitable pulleys to the 70 door-closing device in the doorway, in which device two pulleys *e* and *f* are located, over which the chains run, the pulley *e* being for the chain *c* and the pulley *f* for the chain *d*. These pulleys are so located that the chains 75 may lead downwardly through a passage in two relatively heavy weights *g* and *h*, and on the lower ends of these chains there are secured two smaller weights *i* and *j*, which are merely counterbalancing weights for the 80 door, having the further function of serving as stops for the weights *g* and *h* when the latter are released to close the doors automatically.

The pulleys *e* and *f* are supported in suitable metal brackets *k*, so formed and secured together as to not only support the pulleys *e* and *f*, but also to constitute a suitable support for a bolt *m*, which is capable of endwise and rotative movements in its bearings, 90 the said brackets also providing suitable supports for an L-shaped arm *n*, also capable of endwise movement. On the bolt *m* is a pair of crank-arms, one arm *o* of which has connected thereto a wire *p*, running to some fixed 95 point of support, and in this wire there is con-

nected a strip of easily-fusible metal q . This arm o is located in a substantially vertical position. The other arm r of the pair extends horizontally from the bolt, or substantially so, and by means of a short link s sustains the weight g . One end of the L-shaped arm n , whose position is clearly shown in Figs. 2 and 3, enters loosely the inner end of the bolt m , and passing through the brackets k runs back 5 in a horizontal direction toward the wall on which the brackets are secured and then turns inwardly again through the wall of the bracket at the point t , Fig. 2, this end entering the eye of a short link u , to which the weight h 10 is secured. The end of the bolt m which projects through the side of its supporting bracket toward the door a is of spiral formation, as shown in Fig. 7, and on said door a there is secured the round boss v , whose end 15 is also spirally formed, as shown in Figs. 6. This boss is so located relative to the end of the bolt m that when the door a is closed said boss will lie against the end of said bolt, the high point w of said boss lying against 20 the lowest point x of the spiral on the bolt. The closing of the door, therefore, when the weights g and h are in inoperative position—that is to say, held up by the wire connection p —will not impart any endwise movement to 25 the bolt; but if the fusible strip q is ruptured then the weight g will fall, automatically closing the door a , and in its fall will cause the arm r on the bolt m to swing downward to release the weight, thus bringing the high point of 30 the spiral on the end of said bolt opposite the high point w of the spiral on the boss v . Thus as the door a swings shut it will toward the end of its movement come in contact with the bolt m and impart an endwise movement 35 thereto, which in turn will be imparted to the arm n and disengage the latter from the link u , and thus release the weight h at or near the end of the closing movement of the door a , thereby always insuring the closing of the 40 door b at a time following the closing of the door a —that is, the release of the weight which closes the door b can only be effected 45

at or near the termination of the closing movement of the door a .

Having thus described my invention, what 50 I claim, and desire to secure by Letters Patent of the United States, is—

1. The combination with two doors movable toward each other, of two weights supported adjacent to the doors; and restraining devices 55 to hold the weights normally inactive; a flexible connection extending from each door to and through its actuating-weight, and means on said flexible connections below the weights to support the latter when they are released, together with means to release the weights in succession, to effect the closing of one door after the other.

2. The combination with two doors movable toward each other, of two weights supported 60 adjacent to the doors; and restraining devices to hold the weights normally inactive; a flexible connection extending from each door to and through its actuating-weight, and means on said flexible connections below the weights to support the latter when they are released, together with means to release one of said 65 weights whereby the closing of one door may be effected, and devices on said door coöperating with said weight-restraining devices, 70 whereby the second weight may be released during the closing movement of the first-released door.

3. The combination with two doors movable one toward the other, of a door-closing weight 80 for each door, supported adjacent thereto, and restraining means associated with the weights to hold them normally inactive; means independent of the doors to release one of said weights to effect the closing of one door, and 85 a device actuated by the closing movement of said door to effect the release of the other weight, whereby the second door may be closed after the first.

FRANK M. EDMONDS.
